FRANK W. ROBINSON, OF READING, PENNSYLVANIA, ASSIGNOR TO THE NOLDE & HORST CO., OF READING, PENNSYLVANIA, A CORPORATION OF PENNSYLVANIA.

DROP-STITCH MECHANISM FOR KNITTING-MACHINES.

1,339,715.

Specification of Letters Patent.

Patented May 11, 1920.

Application filed February 20, 1919. Serial No. 278,188.

To all whom it may concern:

Be it known that I, FRANK W. ROBINSON, a citizen of the United States, residing at Reading, in the county of Berks and State 5 of Pennsylvania, have invented certain new and useful Improvements in Drop-Stitch Mechanism for Knitting-Machines, of which the following is a specification.

My invention relates particularly to circular knitting machines adapted to produce stockings having drop-stitch stripes upon the entire leg and upon the upper portion only of the foot; and it consists in the improved needle-operating mechanism hereinafter 10 fully described in connection with the accompanying drawing and the novel features of which are clearly defined in the claims.

Figure 1 is a plan view showing a cam ring having my improvements applied 15 thereto.

Fig. 2 is an elevation of a known type of machine indicating operating means for the movable needle-engaging cams employed.

Fig. 3 is an interior diagrammatic view 20 of the developed cam ring.

Fig. 4 indicates the three different lengths of butts provided upon the otherwise similar needles employed; and Fig. 5 indicates the relative arrangement of these differently 25 butted needles.

Fig. 6 indicates a known continuous stocking-fabric product of my improved machine.

The relative arrangement of the long-butt 30 needles 10, medium-butt needles 11, and short-butt needles 12, in the rotary needle cylinder 1, as indicated in Fig. 5, corresponds with that shown in my prior Patent No. 1,262,568, issued April ninth, 1918; as 35 does also the general knitting action of the needles in producing a uniform drop-stitch effect upon the circularly knitted leg portions of the fabric indicated in Fig. 6, in connection with a solid formation of the 40 reciprocatively knitted heel and toe portions and of the bottom only of the circularly 45 knitted foot portion thereof. My present invention consists in improved needle-operating cam mechanism whereby the actions 50 of the medium-butt drop-stitch needles are specially controlled to avoid any operation thereof during circular knitting, and to secure a tucking action preliminary to the knitting of the heel, as hereinafter fully set 55 forth.

This improved cam mechanism is illustrated in Fig. 1, and described particularly in connection with diagrammatic view Fig. 3, where dotted lines *a* *b* and *c* indicate courses of the long-butt needles 10, medium-butt needles 11, and short-butt needles 12, respectively. As the front half of the stocking is knitted throughout upon the long-butt needles 10, the desired drop-stitch stripes are produced by merely removing corresponding 60 long-butt needles from the cylinder; but the medium-butt drop-stitch needles 11, which must be out of action during the circular knitting of the leg portion of the stocking, are thrown into knitting action for circular 65 knitting of the foot and reciprocal knitting of the heel and toe, and are also specially operated preliminary to starting the knitting of the heel so as to "tuck" or gather a plurality of yarn loops. The purpose of this tucking action is to avoid defective knitting which is otherwise liable to occur through failure of the thrown-in needles 11 to pick up the yarn with regularity, a difficulty which is overcome in my 70 prior patent referred to by providing specially long latches upon certain of the needles 11 but which is differently overcome by the present improved needle operating 75 cams.

Fig. 3 shows the usual top center cam 15, right and left stitch cams 17 and 18, and needle rest 19 forming the normal upper run-way for the needles. Below this needle rest I provide a parallel run-way 20 in which the butts of the lowered drop-stitch needles 11 are idly held during the circular knitting of the striped leg; said upper and lower run-ways however being connected by reversely inclined branches 22 and 23, serving respectively as lowering and raising run-ways for the needles 11. The upper run-way is also provided with a dipped or V-shaped siding 24—25, into which these same needles 11 may be momentarily diverted from the upper 80 run-way to produce the tucking effect referred to.

The lowering of drop-stitch needles 11 into the lower run-way is effected when desired, by throwing a movable selecting cam 105 into the upper run-way at the point of junction with the lowering branch 22. This cam, as shown, has reversely inclined face portions 30—31 forming an inverted V-shape; the face portion 30 being set back 110

so as to permit the passing of the short-butt and medium-butt needles, but engaging the long-butt needles to divert them upward; while the face portion 31 permits 5 the passing of the short-butt needles only and engages the medium-butt needles so as to divert them downward through the lowering branch 22 to the lower run-way 20. To provide for temporarily diverting the 10 needles 11 from their normal path into the dipped siding 24-25, for tucking action, I employ an independently movable tucking cam having similar reversely inclined face portions 35-36 adapted to selectively lower 15 said needles under the fixed stitch cam 17 so as to avoid the latch-clearing movement, while returning them for the taking on of a new or additional loop. To provide for returning the needles 11 from the lower 20 run-way 20 in which they are subjected to no raising or lowering movement, to the upper run-way and normal knitting action, I employ a switch cam 40 movable into said lower run-way at the junction of the raising 25 branch 23; this cam being preferably connected with the tucking cam 35-36 for joint operation, as indicated, inasmuch as the retaining of the switch cam in operative position while the tucking cam is operated, 30 produces no effect.

As indicated in Figs. 1 and 2, the required movements of the selecting cam 30-31, and combined tucking cam 35-36 and switch cam 40, are automatically effected 35 at required times by the usual pattern-controlled cam drum 45 on cam shaft 46; the spring-turned vertical operating shaft 47 being rocked by contact of its rollered arm 48 with proper projections and 40 recesses on the cam drum face, and the spring-retracted shank portions 50 and 51 of the respective cam devices being selectively operated by engagement of a shaft arm 52 with an intermediately pivoted lever 45 53. In Fig. 1 this lever is in normal midway position and both the spring-retracted cam devices are withdrawn; but an inward movement of the shaft arm 52 presses selecting cam 30-31 into action, while an outward movement thereof permits a stronger 50 spring 55 to overcome the retracting spring of combined cam device 35-36, 40 and so set the latter into action.

During the circular knitting of the uniformly striped leg portions indicated in Fig. 6, the medium-butt needles 11 are held to the lower run-way 20 without being subjected to any raising or lowering action; but just before the heel is reached, the 55 switching cam 40 (in connection with tucking cam 35-36) is thrown in to raise them through the connecting branch 23 to the upper run-way; which run they follow with the other needles, excepting that they are 60 diverted in each course into the dipped siding.

ing 24-25 by the tucking cam 35-36 until the latter is withdrawn. This withdrawal occurs after the knitting of several tucking courses during which the needles 11 take on several loops without being raised to latch-clearing height; and knitting then proceeds as usual, first on the medium-butt needles 11 and short-butt needles 12 only to form the heel, second, on all the needles to form the circular foot, and third, on the medium-butt needles 11 and short-butt needles 12 again to form the toe. After the knitting of the toe, a few connecting courses are knitted on all the needles before resuming the knitting of the next leg of the continuous fabric 75 indicated in Fig. 6; the starting of such leg knitting being effected by merely throwing in the dividing cam 30-31 to lower the medium-butt needles 11 into their lower run-way 20 as at the beginning of the described 80 operation.

This lowering of the medium-butt needles to idle position in lower run-way 20, in the knitting of a continuous fabric for ladies' stockings such as is indicated in Fig. 6, takes 85 off the yarn loop on such needles by simply tearing the yarn, which is unobjectionable as the continuous fabric is parted by cutting just beyond the toe. The usual dividing cams shown at 60, 61, need not be employed 90 in connection with the preferred special dividing cams 30-31 and 35-36, but may be employed in place of the portions 30 and 35 of said cams for temporarily raising the long-butt needles 10, which are relowered by a fixed cam 62. The specific mechanism set forth may be readily modified without departing from the invention as defined in the claims.

What I claim is:

105

1. In a knitting machine comprising an approximate half-circle of needles having long butts and an approximate half-circle some of which have short butts and others medium butts; a needle-operating mechanism comprising parallel upper and lower run-ways for the needles connected by separate lowering and raising branches and said upper run-way having also a dipped siding, a selecting cam movable into said upper run-way and operative upon said long-butt and medium-butt needles to lower the latter only into said lower run-way, a switch cam movable into said lower run-way to re-raise said lowered needles, and a tucking cam movable 110 into said upper run-way and operative upon said long-butt and medium-butt needles to deflect the latter only into said dipped siding.

115

2. In a knitting machine comprising an approximate half-circle of needles having long butts and an approximate half-circle some of which have short butts and others medium butts; a needle-operating mechanism comprising parallel upper and 120

125

mechanism comprising parallel upper and

130

- lower run-ways for the needles connected by separate lowering and raising branches and said upper run-way having also a dipped siding, a selecting cam movable into 5 said upper run-way and operative upon said long-butts and medium-butts needles to lower the latter only into said lower run-way, and switch and tucking cams simultaneously movable into said lower and upper 10 run-ways respectively and jointly operative upon said lowered medium-butts needles to traverse them in said dipped siding.
3. In a knitting machine comprising an approximate half-circle of needles having 15 long butts and an approximate half-circle some of which have short butts and others medium butts; a needle-operating mechanism comprising selecting-cam faces movable into the normal runway of the needles 20 and operative upon said long-butts and medium-butts needles to lower the latter only, and a continuous lower run-way for said lowered needles connected with the normal race-way by lowering and raising 25 branches and having a switch cam movable thereinto at the junction of said return branch.
4. In a knitting machine comprising an approximate half-circle of needles having 30 long butts and an approximate half-circle some of which have short butts and others medium butts; a needle-operating mechanism comprising an inverted V-shaped
- selecting cam movable into the normal run-way of the needles and having one member 35 set back to engage and raise the long-butts needles only and the other member set back to engage and lower the medium-butts needles only.
5. In a knitting machine comprising an 40 approximate half-circle of needles having long butts and an approximate half-circle some of which have short butts and others medium butts; a needle-operating mechanism comprising two inverted V-shaped 45 cams separately movable into the normal run-way of the needles at different points thereof, one member of each of said cams being set back so as to engage and raise the long-butts needles only and the other member 50 being set back so as to engage and lower the medium-butts needles only.
6. In a knitting machine comprising an approximate half-circle of needles having 55 long butts and an approximate half-circle some of which have short butts and others medium butts; a needle-operating mechanism comprising connected upper and lower run-ways for the needles the upper one of which has a dipped siding, and a tucking 60 cam and switch cam jointly movable into junction points of said upper and lower run-ways respectively.

In testimony whereof I affix my signature.

FRANK W. ROBINSON.
